LIGHTING DEVICE FOR AUTOMOBILES

Leslie E. Tarbox, North Reading, Mass.

Application April 18, 1934, Serial No. 721,073

9 Claims. (Cl. 240—8.3)

The principal object of my invention is to provide efficient lighting of a number plate, especially the front number plate, of an automobile, particularly in cases where an accident occurs and the offending driver does not remain at the scene of the accident and particularly if a police officer is on the lookout for a particular automobile.

Another object is to provide a firm mounting so that the device will not work loose under the severe jarring conditions commonly experienced in automobiling.

A feature of my invention consists in providing for throwing light across the number plate but preventing the light from being thrown longitudinally of the car as such longitudinal throwing might interfere with the ordinary lighting now used.

Another feature is a special form of reflector. Other features will be pointed out below.

In the drawings

Figure 1 is a front elevation of a device embodying my invention;

Figure 2 is a rear elevation of the same;

Figure 3 is an enlarged section on line 3—3 of Figure 1;

Figure 4 is an enlarged section on line 4—4 of Figure 1;

Figure 5 is an enlarged section on line 5—5 of Figure 3;

Figure 6 is an enlarged front elevation of the wall member described below;

Figure 7 is a bottom plan of the reflector; and

Figure 8 is a fragmentary plan view of the transparent member described below.

I show a front number plate 1 which may be attached to the body of the automobile in any suitable way. Mounted on the number plate is a bracket comprising an upper element 2 having a bent-over part 3 forming a recess to receive a portion of the top edge of the number plate and comprising a lower element 4 having a bent-over part 5 forming a recess to receive a portion of the bottom edge of the number plate. These recesses may, of course, be made of proper dimension to receive varying thicknesses of the edges of the number plate. Element 2 has an integral perforated flange 6 and element 4 has an integral perforated flange 7. A bolt, having a head 8 engaging the top of flange 6, has a shank 9 passing through said perforations, the shank being in threaded engagement with nut 10. Washers 11 and 12 are provided and spring 13 coiled around shank 9 abuts at one end against washer 11 and at the other end against flange 7, the spring acting to lock the nut 10 in the desired position, when the nut has been turned to the desired position, to clamp flanges 6 and 7 and consequently parts 3 and 5 in the desired position with relation to the number plate. Element 2 has in-

tegral extensions 14 and 15, the latter being perforated to receive and hold socket 16 for electric lamp 17, the current coming through wire 18 from any suitable source of supply.

The casing for the lamp includes, as one member, a rear wall 19 held by rivets 20 to the supporting extension 15. This wall has a horizontal forwardly-projecting flange 21 and also a forwardly-projecting curved flange 22. Two tubular posts 23 are soldered at their tops at 24 to the flange 21 and are soldered at their bottoms at 25 to the flange 22. A perforation is provided to register with the perforation in extension 15.

The other member of the lamp casing comprises a horizontal top wall 27, a front wall 28 and a lower curved wall 29 having the opening 30, the latter extending to the points 31 and 32, as shown in Figure 5. The top wall 27 is perforated to register with the tops of tubular posts 23 and the lower curved wall 29 is perforated to register with the bottoms of tubular posts 23.

Packing 33 provides a tight joint between the two members of the casing so as to exclude water, dust or other objectionable matter.

The reflector, made in one piece of any suitable reflecting material, is shown most clearly in Figure 7 and comprises four substantially flat faces 34, 35, 36 and 37, each face being in a plane different from the plane of each of the other three faces. Faces 34 and 35 extend upwardly, transversely of the device, from line 38. Faces 36 and 37 extend upwardly, transversely of the device, from line 39. Faces 34 and 36 extend downwardly, longitudinally of the device, from line 40 and faces 35 and 37 extend downwardly, longitudinally of the device, from line 41. Lines 40 and 41 extend upwardly from their junction while lines 38 and 39 extend downwardly from their junction. This arrangement of the faces is highly effective in directing the light rays downwardly along the face of the number plate and transversely of the device so as to light completely the entire width of the number plate. All four faces of my reflector direct the light out transversely and the front faces throw the light rays down and backward. The reflector is preferably cut away at the corners 42 and 43 for convenience in inserting it into the casing.

A curved plate 44 of transparent material, such as glass, covers the opening 30 and, holds the reflector snugly in position against the top wall 27. The reflector and the glass plate are held against movement longitudinally of the device by their engagement with the flanges 21 and 22 of the wall 19. The glass plate is preferably cut away at its inner corners, as at 51, so as not to interfere with the down slope of faces 34 and 35.

The two members of the casing are held together by pins 45 and 46, each having a shank 47 which passes through a perforation in the top wall 27, and through a tubular post 23, fitting snugly therein, and through a perforation in wall 29. Each pin has a barb or hook 48 so that when the pins are inserted the two members of the casing are securely clamped together and are wedged between the shanks and hooks of the pins. Protuberances 49 are struck out or pressed out from wall 19 and the inward projection 50 on hook 48 springs inwardly beneath protuberance 49 so as to lock the pin firmly in place.

15 The diffusion of different light rays *a* and *b* is indicated in Figure 5, the ray *b* passing just inside of the end of opening 30.

When my device is mounted on the number plate the current comes through wire 18 which 20 may be connected to any suitable source of current within the automobile. The light rays are reflected as described above and light up the number plate not only throughout its entire face but my particular reflector lights the plate evenly 25 all the way across and the extent of the illumination longitudinally and transversely may be regulated by the size of opening 30. The light rays, such as 52, passing directly from the lamp transversely, light up the mud guards or bumper 30 as the case may be so that a driver may be sure of judging distance, for passing purposes, between his own car and an approaching car.

What I claim is:

1. A device of the character described comprising a number plate; a light; a non-transparent casing around said light but having an opening; and a reflector within the casing and having two adjacent plane faces each extending upwardly and outwardly transversely of the device and acting to direct substantially all the rays from said light through said opening downwardly along and across the face of said plate.

2. A device of the character described comprising a number plate; a light; a non-transparent casing around said light but having an opening at its lower portion; and a reflector within the casing and having four faces, each face being in a plane different from the plane of each of the other three faces, and two faces being in 50 advance of the other two, all four faces extending upwardly and outwardly transversely of the device, the two forward faces extending upward and rearward, longitudinally of the device, while the two rearward faces extend upward and forward, longitudinally of the device, said faces acting to direct substantially all the rays from said light through said opening downwardly along and across the face of said plate.

3. A device of the character described comprising a number plate; a light; a casing for said light, said casing comprising two members, one of said members having an opening; and a pin having a shank to engage said members to hold them together and having a hook to engage the outside of the other of said members; and a reflector within said casing to direct rays from said light through said opening along the face of said plate.

4. A device of the character described comprising a number plate; a light; a casing for said light, said casing comprising two members, one of said members having an opening and one of

said members having tubular posts and the other having perforations registering with the posts; and pins engaging said posts and perforations to hold said members together; and a reflector within the casing to direct rays from said light through said opening and along the face of said plate.

5. A device of the character described comprising a number plate; a light; a non-transparent casing surrounding said light but having an opening, said casing comprising two members, one being provided with an outwardly-extending protuberance; and a pin having a shank engaging said members to hold them together, said pin having also a hooked portion, the latter having an inner projection to engage beneath said protuberance to lock the pin against accidental displacement; and a reflector within the casing to direct rays from said light through said opening and along the face of said plate.

6. A device of the character described comprising a front number plate; a light located in front of, and centrally above, said plate; a non-transparent casing substantially enclosing said light but having an opening at its lower portion, the walls of said opening extending upwardly and outwardly transversely of the device; and a reflector within, but separate from, the casing and having two adjacent plane faces extending upwardly and outwardly transversely of the device and located so as to direct substantially all of the reflected rays from said light through said opening downwardly, and evenly sidewise, along the face of said plate.

7. A device of the character described comprising a number plate; a light; a casing for said light and having an opening; a curved transparent plate across said opening; and a reflector within said casing and separate therefrom and having two adjacent plane faces extending upwardly and outwardly transversely of the device and located to direct the rays from said light through said transparent plate on to said number plate; said reflector being held in position by, and between, the edges of said curved transparent plate and said casing.

8. A device of the character described comprising a number plate; a light; a non-transparent casing around said light but having an opening; and a reflector within the casing and having two adjacent plane faces each extending outwardly transversely of the device and also being inclined to the horizontal, said inclination of both faces being in the same vertical direction, said faces acting to direct substantially all of the reflected rays from said light through said opening and along the face of said plate.

9. A device of the character described comprising a number plate; a light; a non-transparent casing substantially enclosing said light but having an opening, the walls of said opening extending outwardly transversely of the device and also in a general vertical direction; and a reflector within the casing and having two adjacent plane faces each face extending outwardly transversely of the device and also being inclined to the horizontal, said inclination of both faces being in the same vertical direction, said faces being located so as to direct substantially all of the reflected rays from said light through said opening along the face of said plate.

LESLIE E. TARBOX.
